UNITED STATES PATENT OFFICE.

TIMOTHY CLEARY, OF SCHUYLERVILLE, NEW YORK, ASSIGNOR TO STANDARD WALL PAPER COMPANY, OF SANDYHILL, NEW YORK.

WALL-COVERING.

No. 807,155.

Specification of Letters Patent.

Patented Dec. 12, 1905.

Original application filed December 5, 1904, Serial No. 235,512. This application filed February 20, 1905. Serial No. 246,498.

To all whom it may concern:

Be it known that I, TIMOTHY CLEARY, a citizen of the United States, and a resident of Schuylerville, in the county of Saratoga and State of New York, have invented a new and Improved Wall-Covering, of which the following is a full, clear, and exact description, this being a division of the application for improvements in the manufacture of wall-coverings, Serial No. 235,512, filed by me December 5, 1904.

The object of the invention is to provide a new and improved wall-covering which has a highly ornamental plush effect.

15 The invention consists of a new article of manufacture—namely, a wall-covering consisting of a fabric body and coating thereon in plush effect.

20 The invention also consists of novel features and parts and combinations of the same, as will be more fully described hereinafter and then pointed out in the claims.

25 A practical embodiment of the invention is represented in the accompanying drawings, forming a part of this specification, in which similar characters of reference indicate corresponding parts in all the views.

Figure 1 is a face view of the improvement. Fig. 2 is an enlarged cross-section of the same, 30 and Fig. 3 is a side elevation of the machine for producing the wall-covering.

The wall-covering illustrated in Figs. 1 and 2 consists of a fabric body A, of paper or other material, provided on its face with a coating A' of a ground color, from which coating, while wet, portions A² are removed by wiping and in such a manner as to give the color-coating a plush or crushed or mottled effect. In order to produce the desired result, I prefer 40 to employ two coöperating machines or devices—such as shown in Fig. 3, for instance—one of the machines being a wiping-machine B and the other an ordinary coating-machine C for coating the surface of the fabric A with a ground color. The machines B and C are more fully shown and described in the application for Letters Patent above referred to, so that further detail description of the same is not deemed necessary.

50 As illustrated in Fig. 3, the framework B' of the wiping-machine B is mounted on the framework C' of the coating-machine C, and the coated fabric body is carried along by an endless apron D, passing over a table E and

around a roller F on the coating-machine C. 55 The wiping-machine B is provided with a traveling endless blanket or apron G, preferably made of woolen cloth and carrying on its surface wipers H, made of chamois or similar soft fabric material, each gathered to form a bunch, as plainly indicated in the drawings. The wipers H are placed suitable distances apart and may be arranged in regular order, according to a predetermined design, or placed at random on the apron. The endless apron G passes under a roller I, journaled in bearings I', held to slide in suitable guideways on the frame C', the bearings I' being adjusted by suitable screw-rods I² or other means, so as to bring the wipers H in proper 70 relation to the body of the wall-covering A directly opposite the roller F, as plainly indicated in Fig. 3, so that the wipers move in contact with the coated surface of the fabric body of the wall-covering A to take up portions of the wet surface to produce a plush effect or graded shading on the coated surface of the wall-covering. The wall-covering and the apron travel in the same direction for the time being. By adjusting the roller 75 I nearer to or farther from the roller F it is evident that the wipers H are pressed with more or less force in contact with the coated surface of the wall-covering to take up more or less of the ground color. By bunching 80 the fabric material forming the wipers H it is evident that an irregular surface is provided on each wiper, and as the latter is pressed in contact with the coated surface of the wall-covering A it is evident that more or less 85 ground color is taken up and a crushed or mottled appearance is produced on the ground color by each bunched wiper.

Having thus described my invention, I claim as new and desire to secure by Letters 95 Patent—

1. As a new article of manufacture, a wall-covering consisting of a fabric body, and a color coating thereon having spaced portions irregular in shape, the color on the irregularly-shaped spaced portions being in varying shades and contrasting with the general surface of the color coating, producing a plush effect.

2. As a new article of manufacture, a wall-covering consisting of a fabric body, and a ground-color coating thereon having spaced portions irregularly separated from each

other by the general surface of the color coating, the coating at each of said spaced portions having irregular gradations of shade, thereby producing a plush effect.

5 3. As a new article of manufacture, a wall-covering consisting of a fabric body, and a color coating thereon having irregularly wiped portions, spaced from each other by the general surface of the color coating, the
10 color coating at the wiped portions being more

or less removed, producing irregular gradations of shade.

In testimony whereof I have signed my name to this specification in the presence of two subscribing witnesses.

TIMOTHY CLEARY.
